UNITED STATES PATENT OFFICE.

JOHN G. LYNN, OF CINCINNATI, OHIO, ASSIGNOR OF ONE-HALF TO RICHARD WOOLEY, JR., OF SAME PLACE.

BOOT AND SHOE PATTERN.

SPECIFICATION forming part of Letters Patent No. 320,149, dated June 16, 1835.

Application filed March 28, 1835. (No model.)

To all whom it may concern:

Be it known that I, JOHN G. LYNN, a citizen of the United States, and a resident of Cincinnati, in the county of Hamilton and State of Ohio, have invented certain new and useful Improvements in Boot and Shoe Patterns, of which the following is a specification.

The object of my invention is to furnish standard or master patterns for boot and shoe makers, so that each can do the work which heretofore could only be performed by a regular skilled pattern cutter and modeler. This I accomplish by making standard or foundation patterns from sheet metal, card-board, or other suitable material, in sets of five sizes and of the exact size for the lasts in the set, and the exact size of the pattern to be cut, and then cutting slots or spaces in these master patterns, which subdivide them in the proper place for the various pieces required to make a complete boot or shoe pattern. These slots or spaces are of the width required for the laps or seams. Thus each subdivision of the pattern for each size is held together as a stencil plate or frame, and the pattern for any style boot or shoe may be marked or cut from it, as also the pattern for the lining. The outlines of the pieces in each set are cut for the highest-cut boot or shoe patterns of its kind, and within these high-cut patterns the subdivisions are marked off in the proper places for any of the various forms or styles in use which will fit the same last.

In the accompanying drawings, forming part of this specification, Figure 1 is a standard pattern in one piece for a walking or lace shoe, upon which are marked lines for cutting patterns for various styles of uppers to fit the same size of last. The button-fly, which is shown in dotted line upon the standard pattern, is also shown detached above the figure. Fig. 2 is a standard pattern for ladies', misses', or children's high-cut button or lace gaiter, showing also in lines marked upon it low-cut button or lace shoe, either plain or foxed. The button-fly pattern, which is marked from the standard pattern is shown in detached view. Fig. 3 is blocking-out pattern for men and boys' plain-front boot. Within the outlines of this pattern are drawn patterns for opera or tongue boot or

for plain congress gaiter. Fig. 4 is the pattern for half of the back of leg for plain boot, showing also the parts for half the back of leg for opera or tongue boot, as well as the half of the counter-cover for tongue-boot and the counter or stiffener for plain boot-back. Fig. 5 shows cutting over pattern after Fig. 3 has been crimped. This gives a cutting-over pattern for plain fronts and opera or tongue boots and front and half of front leg for opera or tongue boot.

Referring first to Figs. 1 and 2, these frames for proper grading are made five in a set, in the following sizes used in the trade: For infants, 1 to 5, inclusive; children, 6 to 10; misses, 11 to 2; ladies, 3 to 7; youths, 9 to 13; boys, 1 to 5; and men, 6 to 10, and upward 11 to 15. Thus these eight sets will furnish complete patterns for cutting, grading, and fitting every size and style of shoe required.

For the prevailing styles of shoes I cut slots in the standard patterns the width of the lap required for seaming the different parts, so that in cutting a pattern for any piece the proper lap will be obtained by marking and cutting upon the side of the slot opposite from the required piece. For instance, it is desired to make the patterns for a congress gaiter, Fig. 1. The proper sized frame being selected, then fold a piece of paper large enough for the vamp *a*. Then lay the metal frame on top, with the line *a'* in line with the folded edge of the paper. Then cut or mark around the vamp from the toe to the opposite side of the vertical slot 1; then up through this slot 1 on the side next the heel; thence along the upper side of slot 2 to the top. This gives the pattern for the vamp. For the foxing-pattern, cut along the upper side of slot 3 from the heel to the toe side of slot 1; thence down the toe side of slot 1 to the bottom; thence along the bottom outline to the heel, and along the heel outline to the top of slot 3. This gives the pattern for the heel or foxing *b*. For the front quarter, cut the outline from point *x* along the front and over the top to a point vertically above the heel side of the slot 4; thence down along the heel side of slot 4 to the lower side of slot 3; thence in the direction of the toe along the lower side of slots 1 to 5.

3 and 2 to the point *x*. This gives the front quarter *c*. For the rear quarter, cut along the front side of slot 5, from the top down to the lower side of slot 3; thence along the lower side of slot 3 to the heel; thence along the outline of the heel upward and over the top to the point where the front side of the slot 5 would meet the top line. This gives the back quarter, *d*. For the elastic gore *e*, cut from the top along the front side of slot 4 and the rear side of slot 5 to the lower side of slot 3. This gives the patterns for the exact size of each part, including the laps for seaming, so that when they are put together with the overlapping seams the outline will be the exact size of the outline of the frame, Fig. 1. For the lining, place the frame upon a piece of paper, and allow one-eighth of an inch all around the frame. This gives the proper size for the lining. For a lace or button-gaiter, do as above directed, omitting to cut through the slots 4 and 5 for the elastic goring; and for a seamless vamp the same rule applies, omitting to cut through the slot 1 between the vamp and the foxing. Tip-patterns are doubled and cut close to the outline of the part *a* for the distance from the toe back required for the tips.

The dotted line *f*, which is preferably perforated in the metal pattern, indicates the outline for the low button or lace shoe, the dotted line *g*, in connection with the outline of the front quarter, gives the button-fly for a high-cut shoe, and the dotted line *h* gives the front quarter for an Alexis shoe, the back quarter for same shoe being indicated by the dotted line *h'* and the outline for the back quarter. It should be understood that these master or standard patterns are for the standard sizes of shoes manufactured for the trade, and upon these standard patterns are to be marked, as indicated by dotted line, the measurements of the standard sizes of either boots or shoes. Say, for instance, that a pattern like Fig. 1 is for a No. 6 shoe or gaiter, then the ankle-measure across on the line *y y* would be eight and one-half inches, the heel-measure across line *z z* twelve and three-fourths inches, the instep across line *w w* nine and one-fourth inches, and the ball-measure across line *v v* eight and one-half inches. This is the standard size; but to make a custom or measured pattern, if the foot-measure vary from the standard measure marked on the frame, take a copy of the frame of the size or number required on smooth stiff paper, point off on the lines *y y*, *z z*, *w w*, *v v* one-half the difference between the actual measure and the measure indicated on these lines, then connect the points by a line as nearly parallel to the front outline as can be made by passing through all these points. This line gives the outline for any shape of shoe desired. For instance, say that the heel measure is thirteen and three-fourths instead of twelve and three-fourths inches, as marked on the pattern, then make a point on the line *z z* one-half inch beyond

the outline of the shoe, and so with all the measurements. If the particular customer measure is one inch larger than the measurements marked upon the standard pattern, then it is evident that the front outline of the paper pattern should be extended one-half inch parallel to the front line of the standard pattern, Fig. 1. The slots for the front and back quarters and the vamp and foxing and goring will be the same.

The above description also applies to ladies', misses', and children's shoes, represented in Fig. 2. The dotted line *f* in that figure gives the outline for the top of a Newport tie or low-cut lady's shoe. The same rule of course applies for measuring always.

The outline of Fig. 3 is the blocking-out pattern for a high boot, and the slots 6 in connection with the outline give the blocking-out pattern for a tongue-boot. For cutting the front of the leg *k*, cut around the outline and along the edges of the slot 6 6 opposite the piece *k*, and for cutting the front we cut along the upper or opposite edges of the slot 6 6 and the outline below it. This is not the exact size required; for after the front is crimped, as seen in Fig. 5, the crimping will vary the size according to the material used. I therefore, by cutting over pattern Fig. 5, have the exact size required after the leather has been crimped.

Fig. 4 shows the half of the back of the leg for plain boot if cut around the outline and omitting the slot 7. To cut the back for an opera or tongue boot, cut around the outline of piece *m* down to the lower side of slot 7 and around the lower side of slot 7; and for the counter or heel part cut around the part *n*, to the upper edge of slot 7 and along said upper edge. This also gives the stiffener for the plain boot leg. It will thus be seen that in one combined pattern—say as in Fig. 1, for instance—I cut the pieces *a*, *b*, *c*, *d*, and *e*, and also the intermediate pieces for a lace or button shoe, and by the whole frame I cut out the lining pattern, making seven pieces for one size; or, in other words, I cut from the set of five pieces thirty-five pieces, all properly graded to fit one with the other in the order required. Besides, I am enabled also to cut the tips and top bands, facings, &c. The same result follows, of course with the ladies' or misses', shoes or men's boots.

As there are few shoe-makers skilled in the art of making patterns and models, the custom shoe-maker has had to buy his uppers from an upper factory or dealer. These uppers are often ill fitting and not of such stock as the custom shoe-maker requires. It will be seen from the foregoing that my invention overcomes this obstacle, as the master patterns are modeled to the usual style of lasts and furnish combinations for all the different styles of boots and shoes known to the trade. With these patterns the custom shoe-maker can cut and fit his own uppers from such stock as he may select.

My invention is also useful to manufacturers, as they can have full sets of patterns cut from these standard frames by any ordinary cutter not skilled in the art of grading, and these sets can be produced quickly by one not an expert pattern grader.

What I claim is—

1. The herein-described master pattern for forming patterns for boot and shoe uppers, which consists of a single piece of the size of the desired upper when seamed together, and having slots, arranged substantially as described, subdividing the said piece for forming the different parts of the upper, the said slots being the width of the lap desired for seaming, so that by marking upon the opposite side of

the slot from the piece desired the exact pattern is obtained.

2. A master pattern, as hereinbefore described, for a high-cut boot or shoe, having 20 the slots, arranged substantially as described, subdividing it for the several pieces, and combined therewith the perforated lines for making patterns for the various styles of boots or shoes which fit the same last. 25

Signed at Cincinnati, in the county of Hamilton and State of Ohio, this 17th day of March, A. D. 1885.

JOHN G. LYNN.
